UNITED STATES PATENT OFFICE.

ARTHUR W. BANISTER, OF BOSTON, MASSACHUSETTS.

DUST COLLECTOR AND SEPARATOR.

SPECIFICATION forming part of Letters Patent No. 651,775, dated June 12, 1900.

Application filed August 30, 1899. Serial No. 728,928. (No model.)

To all whom it may concern:

Be it known that I, ARTHUR W. BANISTER, of Boston, in the county of Suffolk and State of Massachusetts, have invented certain new and useful Improvements in Dust Collectors and Separators, of which the following is a description sufficiently full, clear, and exact to enable those skilled in the art to which it appertains, or with which it is most nearly connected, to make and use the same.

The present invention relates to that type of dust collectors and separators shown and described in Patent No. 600,300, granted to me March 8, 1898; and the prime object in the present case is to provide for classifying the usable products recovered—as, for instance, shavings and sawdust—when the invention is employed in connection with wood-working plants. The separation and recovery of the products are effected by a system of deflection, the current of dust-laden air and other matter entering the separator laterally and impinging against a downward deflector and also encountering lateral deflectors in association with which and with the downward deflector means are employed for classifying the materials, the different grades so recovered being separately discharged.

With the above-stated object in view the invention consists in certain novel features of construction and combinations of parts, the essential elements of which are recited in the appended claims, and a preferred form of embodiment of which is illustrated in the accompanying drawings and specifically described hereinafter.

Of said drawings, Figure 1 represents the apparatus in vertical longitudinal section. Fig. 2 represents the same in end elevation, and Fig. 3 is a horizontal section taken on line 3-3 of Fig. 1.

The exterior casing of the separator, as shown in the drawings, comprises an upper rectangular portion *a*, in the top part of which a chamber *b* is formed by a horizontal partition-plate *c* and a downwardly-inclined deflector-plate *d* joining the back and sides of the casing. An outlet for dust-free air is provided in the top of the casing by a flue *e*, which extends down through the partition-plate *c*, the latter having an opening *c'* sufficiently large to form a passage-way around

the flue, establishing communication between the chamber *b* and the interior of the casing with the purpose of admitting fine particles of dust to said chamber. An outlet from the latter is provided at the back where a nipple *f* projects from the casing just above the lower line of the deflector-plate *d* to discharge into the atmosphere dust so fine as to be almost imperceptible.

The current of dust-laden air and other matter, impelled by a fan or otherwise, enters the casing by a large pipe connection *g* at an upper corner of the front side of the casing and impinges against the deflector-plate *d*, by which it is diverted downward. Other vertically-arranged deflecting-plates *h* and *h'* extend from the sides of the casing at an angle thereto, so as to have the effect of laterally diverting the current simultaneously with its downward deflection.

For the purpose of classifying the material as the current is downwardly and laterally diverted a foraminous or perforated wall or partition *i* is arranged vertically between the deflector-plates *d*, *h*, and *h'*, with which it unites, said partition dividing from the main chamber of the casing an auxiliary chamber *j*, into which particles, such as sawdust, capable of passing through the perforations of the partition may enter.

Below the rectangular portion *a* the casing takes the form of a hopper or chute *k*, the sloping back wall *m* of which unites with the side deflectors *h* and *h'* and with the foraminous partition *i*, extending therefrom on a sufficiently-sharp inclination to insure the sliding down thereon of matter, such as shavings, so large as not to pass through the perforations of the partition. The sides of the hopper are preferably flat, the front side being vertical as a continuation of the front side of the upper portion of the casing, and the other sides slanting and converging to the outlet opening *n*, where a pipe connection is provided. An auxiliary hopper or chute *o* is provided as an appendage to the chamber *j*, so arranged as to receive matter which passes the perforated partition and to discharge the same through a pipe connection *o'* at the bottom of the hopper.

A horizontal plate *p* may be secured within the casing between the main chamber of the

rectangular part thereof and the top of the hopper *k*, said plate being connected with the sides of the casing by arms *p*' and serving to prevent an upward current or the return of matter from the hopper, while at the same time giving ample space for downward passage of materials to be recovered.

Sufficient statements of operation have been coupled with the description of the construction of the apparatus here shown to make unnecessary any further explanation as to the mode of operation.

It is to be understood that the invention herein disclosed may be embodied otherwise than as shown in the drawings and specification, and hence the appended claims are not limited to any one particular form of construction.

Having thus explained the nature of the invention and described a way of constructing and using the same, though without attempting to set forth all of the forms in which it may be made or all of the modes of its use, it is declared that what is claimed is—

25 1. A dust collector and separator comprising an inclosure having at one side a lateral inlet for material to be separated, a perforated or foraminous vertical wall at the opposite side of the inclosure, downward and lateral 30 deflectors extending from top and side walls respectively of the inclosure to the top and the sides respectively of the said foraminous wall, separate downward deliveries on opposite sides of the latter, and an air-outlet at 35 the upper part of the inclosure.

2. A dust collector and separator comprising a casing having a lateral inlet at the upper part for material to be separated, a downward deflector opposite said inlet and extending 40 from side to side of the casing and between a top and rear wall of the same, a vertical foraminous partition extending downwardly from said deflector providing a chamber between said rear wall of the casing and 45 said partition, a hopper-like appendage to said chamber having a discharge-outlet at the bottom, one or more lateral deflectors extend-

ing from the side walls of the casing to the sides of the foraminous partition, a hopper-like lower portion of the casing meeting the latter and the lateral deflectors, and an air-outlet in the top of the casing, substantially as described.

3. A dust collector and separator comprising a casing having a lateral inlet at the upper part for material to be separated, a deflector opposite said inlet and arranged to divert the current of material downwardly, a perforated or foraminous partition extending downwardly from said deflector, deflectors 60 extending between the sides of the casing and the said foraminous partition, tapering outlet-chutes on opposite sides of said partition, and an air-outlet at the top part of the casing.

4. A dust collector and separator comprising a casing having a substantially-rectangular upper portion with a top chamber in communication with the main portion of the casing, an air-outlet flue in the top of the casing and extending through said chamber, a lateral outlet from the latter, a lateral inlet to the rectangular part of the casing immediately below the top chamber, a deflector extending across the casing opposite said lateral inlet and forming part of the bottom of the said top chamber, said deflector being designed to divert the incoming current downward, a foraminous partition extending downwardly from said deflector, deflectors extending between the sides of the casing and said partition and designed to divert the current laterally, and tapering discharge outlets or chutes on opposite sides of the foraminous partition.

In testimony whereof I have signed my name to this specification, in the presence of two subscribing witnesses, this 28th day of August, A. D. 1899.

ARTHUR W. BANISTER.
